UNITED STATES PATENT OFFICE.

ERNEST MONTELEONE, OF JERSEY CITY, NEW JERSEY.

DESIGN FOR A TOY AEROPLANE.

56,185.

Specification for Design. Patented Aug. 24, 1920.

Application filed June 16, 1919. Serial No. 304,713. Term of patent 7 years.

To all whom it may concern:

Be it known that I, ERNEST MONTELEONE, a citizen of the United States, residing at Jersey City, in the county of Hudson and State of New Jersey, have invented a new, original, and ornamental Design for Toy Aeroplanes, of which the following is a specification.

In the drawing accompanying,—

Figure 1 is a plan view;

Fig. 2 is a front elevation; and
Fig. 3 is a side elevation of a toy aero-
plane embodying my design.

I claim:
The ornamental design for a toy aero-
plane as shown.

ERNEST MONTELEONE.
